UNITED STATES PATENT OFFICE

2,443,140

BOIL CUP

Robert E. Larsen, Chicago, Ill.

Application April 11, 1946, Serial No. 661,431

1 Claim. (Cl. 128—154)

1

The present invention relates to improvements in therapeutic applicators and more particularly to a means for enclosing protectively a boil or other protuberance or erupted area upon anatomical tissue for the purpose of administering relief by means of a medicament.

One of the objects thereof is to provide a simple, efficient and inexpensive boil cup so shaped, arranged and functioning that, when attached adhesively to anatomical tissue of a person suffering from a boil and/or similar skin affection, and made to enclose and cover the protuberance, contact between an ointment, salve or other medicament contained in the cup concealedly may be had with the sore.

Another object thereof is to provide a boil treating unit which is characterized by the fact that it encloses and covers so as to protect from tactual contamination a painful protuberance such as a boil present upon the tissue of a sufferer, and at the same time, administers thereon a local medicament housed therein.

A further object thereof is to provide a dependable, readily serviceable bandage-like aid in connection with the treatment for relief purposes of a painful boil or similar skin protuberance, which lends itself to instant application to the seat of the skin affection and which can readily be removed therefrom at will.

With the above and other objects in view, my invention consists in the combination, arrangement and details of construction disclosed in the drawings and specifications, and then more particularly pointed out in the appended claim.

In the drawings, wherein similar reference characters designate similar parts throughout the respective views,

Figure 1 is a bottom plan view of my invention,

Figure 2 is a longitudinal section thereof, and

Figure 3 is a bottom plan view of a reticulated member mounted in the invention for holding a medicament, hereinafter described.

In the drawings, which are merely illustrative of my invention, all details of my invention are set forth.

I contemplate producing a bandage-like unit where adhesive and not wrapping qualities inheres in the bandage. For this purpose I take a piece of adhesive tape or adhesive material or fabric and shape it to the outline desired, which may be curvilinear or polygonal as may be desired. In the drawings is illustrated a disc-like piece of adhesive material 10, having the circular perimetral edge 11. Formed upon the

2

perimeter of this piece of adhesive material are a radiating series of arms or flanges, of which four are shown designated 12, 13, 14, and 15. The inner planes of these arms have a curvilinear connection as at 16 with the perimeter 11 of the adhesive material.

I also contemplate employing, if desired, a sheet of gauze to overlie the adhesive face of the adhesive material 10, for the purpose of protecting this surface against adhering to whatever comes in contact with it prematurely, before actually employing the invention in use for the purpose for which it is intended.

The adhesive material is formed with a central opening of cylindrical shape designated 17. The adhesive substance or lamination on the material 10 is designated 18 and extends coextensively with all parts of the material, and where the arms 13, 14, 15, and 16 are formed upon the material 10, this adhesive lamination is placed thereon as at 14a, 12a, etc.

A concavo-convex hollow cup-shaped body is employed and centered with the central opening 17 of the material 10 in such a manner that it opens out of this material by way of this opening. This body may be made from any approved pliable or semi-hard material such as hard rubber, papier mâché, plastic or similar materials. The cup-shaped body is designated 19. It is formed with a circular base flange or with a radiating series of arms similar to the arms formed upon the adhesive material, as may be described. If the material of adhesive quality is thick enough it is intended to skive same so as to taper it from the opening to a thin feather edge at the ends of the disc-shaped part thereof. However, by skiving only the base portion 20 of the cup shaped body 19, the same result contemplated may be produced—to anchor the cup shaped body 19 in such a manner overlappingly upon the adhesive material or disc 10, that its outer face is flush with the adhesive outer face of the material 10.

By skiving the base portion of this body 10 it starts to taper away from the base of this body as at 21 until a feather thin edge 22 is produced perimetral of this base portion. This thinned out base portion is then laid in contact over the outer adhesive face of the material 10, and the extra adhesive substance may be spread out at 23 between the skived surface of the base portion 20 and the adjacent surface of material 10, so as to fill any unevenness between both and make a flush applying surface for the bandage part of this invention.

A circular series of vent holes 24 are formed upon the body 19 in close contiguity to the material 10. The body is also provided with a circular series of inwardly struck integral lugs 26 punched out from openings or slots 25 therein. These lugs are caused to provide a shelf in a plane at right angles to the axis of the cup shaped body 19. These lugs 26 are located in back of the vent holes 24, or nearer to the inner part of the cup shaped body than the vent holes.

For the purpose of providing a means of housing usefully a medicament, salve or ointment in the bottom of the body 10, I employ a disc of cardboard or other soft pliable material, as shown at 27, which is formed with a central hole 29 which is covered by a foraminous piece of material or gauze 28. This disc with its reticulated central part is laid in contact with the upper faces of the lugs 26 which compose the shelf and attached thereto in any desirable manner. This centers the reticulated piece 28 properly at a medial line of the cup-shaped body 19.

This cardboard disc 27, partitions off the cup-shaped body into two compartments, an inner one and an outer one 30a which opens directly out of the body and adhesive material 10. A suitable salve, ointment or other medicament 30 is held in the inner compartment 31, being confined in this compartment by the disc 27 and its foraminous part 28.

The use and function of the invention is to protect and cover the oil or other protuberance on the skin of the sufferer. For this purpose the cup-shaped body 19 is placed in covering position over the boil by pressing its mouth 30a against the affected zone of the skin in a manner to

receive into this compartment and enclose the boil. The adhesive surface 23 of the bandage-like material 10 is then caused to adhere to the skin, to hold the cup-shaped body securely in covering position. The ointment begins to give off its therapeutic qualities at once by way of the pores of the reticulated piece 28, and the soreness is soothed in time. Suitable ventilation interiorly of the body 19 is permitted by way of the vent holes 24 which assist in stimulating the soothing action of the medicament 30.

What I desire to claim and secure by patent is:

A medicament applicator comprising a cup-shaped member, a flange carried by said member, adhesive means for securing said member to an affected part, inwardly struck lugs carried by said member, a medicament supporting disk engaging the inner sides of said lugs and formed with a relatively large central opening, said lugs being bent downwardly and inwardly and thereby forming vent openings above said disk, and a pervious member interposed between said disk and said lugs.

ROBERT E. LARSEN.
